GRINDING MACHINE

Henry W. Larsson, deceased, late of Albany,
Calif., by Josephine D. Larsson, executrix,
Albany, Calif.

Application December 1, 1937, Serial No. 177,625

9 Claims. (Cl. 51—92)

This invention relates to a grinding machine which is particularly intended for grinding reamers, milling cutters, and like metal cutting tools. Reamers, milling cutters, and like metal cutting tools as received from the factory are usually ground with a cutting clearance of five degrees. This clearance may be decreased when used on heat-treated alloy steel and may be increased for excessively soft steel. Cutting clearance is a function of many variables, such as hardness and toughness of the material being worked upon, the cutting speed employed, table feed, the condition of the machine, etc., and can best be determined by experience and the particular work in hand. All cutting tools of this character have a plurality of teeth, the front and outer ends of which form the cutting edges, and the clearance employed is determined when grinding the lands or the surfaces directly behind the cutting edges, the lands usually being flat or hollow ground. Hence, the greater the clearance employed, the weaker the cutting edge, as the backing which supports the cutting edge becomes less as the clearance increases, and the tool will accordingly require frequent regrinding. It might also be pointed out that two lands are usually employed, to-wit, a primary land and an intermediate land which are separately ground. The primary land is directly behind the cutting edge and is from one-sixteenth to one-eighth of an inch wide, while the intermediate land is much wider and is disposed on a greater angle to materially increase the clearance. In regrinding the cutter, three operations are necessary, first, grinding of the exterior surface to a true cylinder, secondly, grinding of the primary land, and third, grinding of the intermediate land. These several operations take considerable time and are costly, as skilled operators are necessary.

The object of the present invention is to generally improve and simplify the construction and operation of grinding machines, and especially to provide a machine whereby a convex arcuate surface or single land is formed behind the cutting edges of a tool, as such a surface provides a gradually increasing clearance which does not materially weaken the backing behind the cutting edges of the teeth and which furthermore does away with the primary and intermediate lands and reduces the regrinding of a tool to one single operation; to provide means whereby the radius of the arcuate surfaces may be increased or decreased; to provide means whereby the final clearance produced by the arcuate surface may be varied; and further, to provide means where-

by an exact placement or position between the grinding wheel and each tooth to be ground is maintained so that uniform grinding of each tooth of a cutting tool will result.

In the drawings—

Fig. 1 is a diagrammatic view showing the manner in which form cutters are ground;

Figs. 2 and 3 are diagrammatic views showing the standard method of grinding profile cutters;

Fig. 4 is a diagrammatic view showing the grinding of profile cutters by the method forming the subject matter of the present application;

Figs. 5 and 6 are diagrammatic views showing the effect of offsetting the dressing tool during the shaping or dressing of the peripheral face of the grinding wheel;

Fig. 7 is a perspective view of the grinding machine;

Fig. 8 is an enlarged plan view of the grinding head;

Fig. 9 is a front view of the grinding head, part of the column being shown in section;

Fig. 10 is a side elevation of the grinding head looking in the direction of arrows X—X, Fig. 9;

Fig. 11 is a side elevation of the grinding head looking in the direction of arrows XI—XI, Fig. 9; and

Fig. 12 is a vertical section of the column and the housing at the upper end thereof, said section also showing the spindle bearings and the spindle journaled therein.

The grinding machine forming the subject matter of this application is particularly intended for grinding profile cutters such as multiple-fluted, straight, or helical reamers, and milling cutters of varying shapes, except that type known as "form cutters" because the relief or land back of the cutting edges of a form cutter is pre-formed in the factory and is sharpened by simply grinding the front cutting face of the tooth in a plane parallel to the axis of rotation as shown at 1 in Fig. 1. Profile cutters, on the other hand, are ground on the outer or land surfaces rearwardly of the cutting edges as shown at 2 and 3 in Fig. 2, or as at 4 and 5 in Fig. 3, Fig. 2 showing a primary land 2 which is flat ground, and Fig. 3 a primary land which is hollow ground. The machine is not only intended for grinding profile cutters, but also to form a new shape or form of land behind the cutting edge which will hereinafter be referred to as a radial or arcuate land, as shown at 6—6 in Fig. 4. Actual prac-

tice has shown that the grinding of an arcuate land of the type shown in Fig. 4 provides a better backing for the cutting edge, causing it to stand up longer, and therefore requires less frequent 5 resharpening, it reduces the tendency to dig in and chatter, and produces a smooth finished surface and furthermore reduces the time and cost of regrinding, as one single grinding operation is all that is required to resharpen the tool as 10 compared with the three grinding operations required when a tool is ground according to standard practice as shown in Figs. 2 and 3. The radial or surface ground behind the cutting edge of a tool by the machine forming the subject 15 matter of the present invention will be of increasing radius as the diameter of the cutter increases, and the clearance provided by the radial land or surface will vary in accordance with the character of the metal being worked upon; i. e., 20 a hard steel or metal will require the least clearance and a softer steel a greater clearance. The radial land is of course imparted to a tooth by a grinding wheel, and in order that the grinding operation be as simple as possible and that it be 25 completed in one operation, the outer edge of the wheel will be dressed or shaped to the exact contour or radius required.

One of the features of the present invention is accordingly that of providing a cutting or dressing means whereby the outer face of the grinding wheel may be properly dressed or shaped and maintained during a grinding operation. Another important feature is the provision of means whereby an exact placement or position between 30 the grinding wheel and each tooth is maintained 35 so that the radial land or surface ground behind the cutting edge of each tooth will be exactly the same. In order that these and other features of the invention will be more clearly understood, 40 a detailed description of the construction and operation of the machine will be submitted.

Referring to Figs. 7 to 11, inclusive, 10 indicates a pedestal or base upon which is mounted a work supporting table 11. Extending through 45 the top of the base at the rear of the table 11 is a column 12, and secured on the upper end thereof is a housing 14 which functions as a support for a grinding head generally indicated at 50 B. Two vertically disposed guideways 15 and 16 form an integral part of the housing. Mounted on the guideway 16 is a slide plate 17 and carried thereby is a secondary slide plate 18 to 55 which is fixed a bracket 19 upon which is slidably mounted a carriage 20. The plates 17 and 18 are vertically movable on the guideway 16 through means of a hand wheel 21 and a screw feed rod 22 actuated thereby, said screw rod extending through a nut 23 fixed to the guideway 16 so that when the rod is rotated, vertical movement will be imparted. The secondary slide plate 18, while movable in unison with the plate 17, is also movable independently thereof, as a 60 shaft 24 which is provided with a turn knob 25 is journaled in the slide plate 18 and carries a small gear 26 which meshes with a gear rack 27 secured on the face of the plate 17.

The bracket 19 is also provided with a guideway upon which the carriage 20 is slideable cross-wise of the bracket or, in other words, to or 70 away from the slide plates 17 and 18. A screw feed operated by a turn knob 28 similar to that described in connection with the plate 17 is employed to transmit the transverse movement. The purpose of the movable slide plates and carriage will hereinafter be described.

Extending through the housing centrally between the guideways 15 and 16 is a spindle 29, on the outer end of which is mounted in the usual manner a grinding wheel 30. The spindle and the wheel attached thereto may be driven 5 in any suitable manner, for instance, by a pulley 31 which is belt driven, as shown in Fig. 12, and bearings 32 and 33 are provided for its support.

The carriage 20 functions as a support for a 10 diamond cutter 35 whereby the outer peripheral face of the grinding wheel is shaped or dressed, and as one of the features of the machine is the grinding of radial contours in back of the cutting edges of the teeth of cutting tools such as 15 milling cutters, reamers, etc., a mounting must be provided whereby the cutter 35 may be moved across the face of the grinding wheel to dress it to the radial surface or contour required. This is accomplished as follows: Suitably secured to 20 the upper surface of the carriage 20 is a bearing 36 in which is supported a sleeve 37 which is provided with a knob 37a on its outer end. The sleeve is longitudinally movable in the bearing 36 for purposes hereinafter to be described, and its 25 movement is limited by a pin 38 projecting into a groove 39 formed in the upper surface of the sleeve, said pin and groove also securing the sleeve against rotation in the bearing. While the sleeve is longitudinally movable, it is normally clamped and secured against longitudinal movement as one end of the bearing is slotted longitudinally as shown at 40, and is actuated by a clamping lever 41. Extending through the sleeve is a rod 42, the outer end of which is provided with a turning knob 43, while the inner end carries a holder 44 through which extends at right angles to the rod a cutter bar 45 on the inner end of which is mounted the diamond cutter 35. The bar is secured in the holder by 40 a set screw 46, said screw also permitting adjustment of the bar to increase or decrease the radial arc or sweep of the cutter 35. The rod 42, together with the holder 44 and the cutter bar 45 extending therethrough, is always free for 45 rotational movement with relation to the sleeve 36, but such movement is limited by a pin 47 in the holder which engages opposite ends of a shoulder 48 formed on the inner end of the sleeve.

It was previously stated that the housing 14 had two guideways 15 and 16 formed thereon. The guideway 16 with the several parts carried thereby, which function as an adjustable support for the diamond cutter or dressing tool, has been described. Of substantially equal importance is the guideway 15, as it functions as an adjustable support for a steady rest finger whereby a predetermined position is maintained between each tooth of a tool to be ground or sharpened, and the contoured face of the grinding wheel. The steady rest finger is indicated at 58 and is adjustably secured as at 51 in the lower end of an arm 52 which in turn is adjustably secured as at 53 to a slide plate 54 vertically movable on the guideway 15. The sliding plate 17, as previously stated, is moved vertically on the guideway 16 by means of the hand wheel 21 and the screw feed or rod 22. This movement is transmitted to the slide plate 54 through means of a gear 55 which is journaled on and freely 70 rotatable about the inner spindle bearing. The gear is in continuous mesh with gear racks 56 and 57 secured to the respective sliding plates 17 and 54. Thus, if the plate 17 is moved downwardly to bring the diamond cutter 35 closer to 75

the face of the grinding wheel, reverse movement will be transmitted through the gear 55 to move the slide 54 upwardly, thereby maintaining a constant relative position between the dressing tool and the steady rest finger, and at the same time a fixed predetermined position between the contoured face of the grinding wheel and the teeth of the tool to be ground.

In actual practice, the face of the grinding wheel will have to be dressed or reshaped for each milling cutter or reamer to be ground, i. e., if their diameters vary, as the radial contour will vary in proportion to the exterior diameter of the tool to be ground. For instance, if a milling cutter such as shown at 70 in Fig. 7 is to be ground, the exterior diameter of the cutter is first measured, and if the diameter is two and three-quarters inches, the radius of the contour will be one-half that, or one and three-eighths inches. Knob 25 is then grasped and rotated until the "0" mark on the sliding plate 18 registers with one and three-eighths inches on the scale indicated at 71 (see Fig. 10). This operation raises the carriage together with the diamond cutter or dresser to a point one and three-eighths inches above a setting plate 72 (see Figs. 9 and 11). The clamping lever 41 is then released sleeve 37 is grasped by the knob 37a, and pulled outwardly until stopped by pin 38, at which point the cutter bar will align with the setting plate 72. The set screw 46 is then released and bar 45 is pushed downwardly in the holder 44 until the diamond cutter or dresser 35 rests on the setting plate, set screw 46 is again tightened to secure the bar, and sleeve 37, which supports the holder and cutter bar, is then pushed back to normal position where it is again stopped by pin 38 and again clamped by the lever 41. In this position the cutter bar is swung back and forth 40 across the face of the grinding wheel between the limits established by the pin 47 and the opposite ends of the shoulder 48 which it contacts, and as the radius of swing is one and three-eighths inches, the face of the wheel will be dressed or contoured to a radius of one and three-eighths inches.

By referring to Fig. 10 it will be noted that the bracket supporting the carriage 20 carries a graduated scale 16, and the carriage a "0" mark. If the "0" marks on the scale and carriage register while the face of the grinding wheel is being dressed the tool to be ground will have no clearance behind the cutting edges of the teeth, as a true cylindrical surface having a radius of one and three-eighths inches will result, as diagrammatically illustrated in Fig. 5. On the other hand, if the carriage 20 is moved by means of its screw feed in a direction toward the slide plate 18, a radial contour will be formed on the face 50 of the grinding wheel such as shown in Fig. 6, which will give a clearance. Each graduation on scale 16 represents a clearance of .002 of an inch, and if the carriage is moved to the position shown in Fig. 10, a clearance of .004 of an inch 55 will result as the "0" mark registers with the second graduation beyond the "0" mark on the scale. Any clearance may be given, but the range of the scale shown at 72 is .012, as six graduations are provided. To further illustrate the manner in which clearance is obtained reference 60 will be made to Figs. 5 and 6. The radial dimension of the milling cutter shown at 70 is one and three-eighths inches. If a compass is placed at the center 79 of the cutter, and a circle is 65 drawn with a one and three-eighths radius, the

outer surfaces of the teeth will show a true cylindrical surface as indicated at 80. On the other hand, if the point of the compass is moved to one side of the center 79 or the point 81, the outer faces of the teeth will have the surface indicated at 82, thereby providing a clearance behind the cutting edges of the teeth which gradually increases and assumes the greatest dimension at the rear of the teeth as indicated at 83. In other words, the effect of adjusting or moving the carriage toward the slide 18 is just the same as offsetting the centers 79 and 81 in Fig. 6, the result being that the greater the offset the greater the final clearance on the teeth being ground.

After the grinding wheel has been dressed, the milling cutter 70 is secured on the arbor 85 (see Fig. 7) which is supported between the head and tail stock of a carriage mounted on the work supporting table. The whole grinding head is then lowered to grinding position by lowering the column which supports the grinding head through means of a screw feed actuated from the front of the pedestal by a hand wheel 86. With the steady rest finger in proper position, the face 87 of a tooth (see Fig. 10) is brought against the finger and the carriage on the work supporting table is then moved back and forth under the grinding wheel. Each tooth is thus ground in successive order and if a second or third grind 30 is necessary to impart the proper contour and complete sharpening, the operation is merely repeated. Inasmuch as an exact position is maintained between the contoured surface of the grinding wheel and each tooth to be ground, 35 by means of the steady rest finger, and in view of the fact that the dressing tool or cutter 35 cannot be moved without moving the steady rest finger, as they are connected to move in unison through gear 55, it is obvious that four important 40 elements are always retained in a predetermined position with relation to each other, these elements being the dressing tool, the steady rest finger, the tooth to be ground, and last but not least the contoured face of the grinding 45 wheel.

Once a milling cutter, reamer, or similar tool has been ground or sharpened in the manner here described, the grinding operation when re-sharpening is easily and quickly accomplished 50 as only one face of each tooth is ground, and one set-up and grind completes the job. Due to the fact that the steady rest finger and the diamond cutter or dresser are inter-connected and move in unison, their relative position with relation to the face of the grinding wheel never changes, and uniform accurate grinding of tools results. By this method of shaping and grinding the teeth of a tool, more stock is left directly behind the cutting edges to support and back them 60 up with the result that the cutting edge stands up longer and requires less frequent resharpening. Also, it has been found that the tools when ground as here described have less tendency to dig in and chatter, and that a higher finished and 65 almost polished surface is obtainable, particularly with a finishing reamer.

In actual operation, the best clearance for any particular job is found by practical experience, and once this has been established, a 70 written record thereof is made so that any tool may be reground with that particular clearance, this being possible as scales are provided which permit resetting of the diamond dresser to produce an exact duplicate regrind of the tool. 75

Having thus described the invention, what is claimed and desired to secure by Letters Patent is—

1. In a grinding machine of the character described, a grinding wheel, a dresser bar with a cutter member at one end thereof, a pivotal support for the dresser bar to permit swinging of the bar and cutter member across the peripheral face of the wheel to cut a radial contour in the face thereof, means for raising or lowering the pivotal support to permit cutting of radial contours of varying radial dimensions, a steady rest finger disposed adjacent the wheel, to maintain a predetermined position between each tooth of a tool to be ground and the contoured face of the grinding wheel, and means for moving the cutter bar and steady rest finger in unison to and away from the contoured face of the wheel.
2. In a grinding machine of the character described, a grinding wheel, a dresser bar with a cutter member at one end thereof, a pivotal support for the dresser bar to permit swinging of the bar and cutter member across the peripheral face of the wheel to cut a radial contour in the face thereof, means for raising or lowering the pivotal support to permit cutting of radial contours of varying radial dimensions, means for laterally adjusting the cutter bar with relation to the wheel to further vary the radial contour cut in the face of the wheel, a steady rest finger disposed adjacent the wheel to maintain a predetermined position between each tooth of a tool to be ground and the contoured face of the grinding wheel, and means for moving the cutter bar and steady rest finger in unison to and away from the contoured face of the wheel.
3. In a grinding machine of the character described, a grinding wheel, a pivotally mounted dresser bar having a cutter member at one end thereof disposed adjacent the wheel and adapted to swing crosswise of the peripheral face of the wheel to cut a radial contour in the face of the wheel, a steady rest finger also disposed adjacent the wheel to maintain a predetermined position between each tooth of a tool to be ground and the contoured face of the wheel, and means for maintaining a constant relative position between the cutter bar and the steady rest finger.
4. In a grinding machine of the character described, a grinding wheel, a pivotally mounted dresser bar having a cutter member at one end thereof disposed adjacent the wheel and adapted to swing crosswise of the peripheral face of the wheel to cut a radial contour in the face of the wheel, a steady rest finger also disposed adjacent the wheel to maintain a predetermined position between each tooth of a tool to be ground and the contoured face of the wheel, and means for moving the cutter bar and steady rest finger in unison an equal distance to and away from the contoured face of the wheel.
5. In a grinding machine of the character described, a grinding wheel, a pivotally mounted dresser bar having a cutter member at one end thereof disposed adjacent the wheel and adapted to swing crosswise of the peripheral face of the wheel to cut a radial contour in the face of the wheel, a steady rest finger also disposed adjacent the wheel to maintain a predetermined position between each tooth of a tool to be ground and the contoured face of the wheel, means for moving the cutter bar and steady rest finger to and away from the contoured face of the wheel, and a connection between them whereby when

they are moved they will move in unison and an equal distance.

6. In a grinding machine of the character described, a main base, a grinding head mounted thereon, a spindle supported grinding wheel journaled in the head, a pivotally mounted cutter bar mounted on the head and adapted to be swung across the peripheral face of the grinding wheel to cut a contoured face therein, a work supporting carriage on the base to receive and support a tool to be ground, means for moving the head to and away from the tool to be ground, means for increasing or decreasing the radial length of the cutter bar with relation to its pivotal support, a steady rest finger carried by the head and engageable with the teeth of the tool on the carriage to maintain a predetermined position between the contoured face of the wheel and the teeth of the tool while they are being ground, and means on the head for maintaining a constant relative position between the cutter bar and said finger.

7. In a grinding machine of the character described, a grinding wheel, a dresser bar having a cutter member at one end thereof, a holder in which the dresser bar is adjustably secured to lengthen or shorten the distance between the holder and cutter member, a pivotal support for the holder to permit the cutter member to be swung across the peripheral face of the grinding wheel to cut a radial contour therein, a setting plate disposed at one side of the grinding wheel, means for moving the dresser bar and cutter member into alignment with the setting plate when the radial swing of the cutter member is to be changed, means for releasing the dresser bar with relation to the holder to permit the cutter member to rest in the setting plate, and means for raising or lowering the holder to lengthen or shorten the radial swing of the cutter member.

8. In a grinding machine of the character described, a grinding wheel, a dresser bar having a cutter member at one end thereof, a holder in which the dresser bar is adjustably secured to lengthen or shorten the distance between the holder and cutter member, a pivotal support for the holder to permit the cutter member to be swung across the peripheral face of the grinding wheel to cut a radial contour therein, a setting plate disposed at one side of the grinding wheel, means for moving the dresser bar and cutter member into alignment with the setting plate when the radial swing of the cutter member is to be changed, means for releasing the dresser bar with relation to the holder to permit the cutter member to rest in the setting plate, means for raising or lowering the holder to lengthen or shorten the radial swing of the cutter member, and a graduated scale with relation to which the holder moves so that the radial swing of the cutter member may be measured and indicated.

9. In a grinding machine of the character described, a main base, a grinding head mounted thereon, a spindle supported grinding wheel journaled in the head, a carriage on the head, a bearing on the carriage, a sleeve in the bearing, a rod in the sleeve, a holder on one end of the rod, a cutter bar extending through the holder and having a cutter member at one end thereof, said rod and holder forming a pivoted support for the cutter bar to permit the cutter member to be swung across the peripheral face of the grinding wheel to cut a radial contour therein, a setting plate disposed at one side of the cutting wheel, means permitting longitudinal movement of the sleeve, rod, holder and cutter bar to a position

where the cutter member aligns with the setting plate, releasable clamping means on the holder to permit the cutter bar to be moved in the holder until the cutter member rests on the setting plate, means for raising or lowering the carriage together with the bearing, the sleeve, the rod and the holder to lengthen or shorten the radial swing of the cutter member, said clamping means on the holder being clamped when the cutter bar is 5 adjusted and said sleeve, rod, holder and cutter

bar being moved longitudinally in the bearing back to the grinding wheel after the cutter bar is clamped, and means for clamping the sleeve in the bearing, said clamp leaving the rod and the holder free to swing the cutter member across 5 the face of the grinding wheel.

JOSEPHINE D. LARSSON,
Executrix of the Estate of Henry W. Larsson,
Deceased.
